DIVING AND LIFE SAVING PLATFORM

Louis Giliasso, New York, N. Y.

Application April 23, 1934, Serial No. 721,897

8 Claims. (Cl. 4—171)

The present invention relates to diving and life saving equipment used at bathing beaches.

In ordinary practice, a float is anchored at some distance off shore and this float carries one or 5 more diving boards and sometimes an elevated station for the life guard. These floats are dangerous to swimmers and provide an unstable support both for diving and life saving purposes. Furthermore, they require constant attention, 10 pumping out and the like, and are quite expensive.

The objects of this invention are to provide a support for diving, life saving and other purposes, which will be substantial and stable when 15 in use, inexpensive to maintain and which when not in service, may be readily removed and suitably stored.

The foregoing and other desirable objects are attained by the novel features of construction, 20 combinations and relations of parts hereinafter described, illustrated in the accompanying drawings and broadly covered in the claims.

The drawings accompanying and forming part of the specification illustrate certain practical 25 embodiments of the invention, but it will be appreciated that the structure may be modified in various respects without departure from the true spirit and broad scope of the invention.

Fig. 1 is a broken plan view of one embodiment 30 of the invention.

Fig. 2 is a broken vertical sectional view of the upper portion of the same as on line 2—2 of Fig. 1.

Fig. 3 is a broken plan view of the submersible 35 barge structure which forms the sunken foundation.

Fig. 4 is a broken side elevation illustrating some modifications in structure.

In the several views, a foundation barge is 40 shown at 5, of a suitable size and buoyancy both to form a substantial base when sunk on bottom as in Fig. 2 and to carry a trestlework 6, supporting an elevated platform 7, above the water level such as indicated at 8.

This elevated platform may be as simple or as 45 extensive as desired and be one continuous platform as in Fig. 4, or be simply a more or less narrow walk-way about an open center well as in Figs. 1 and 2.

This well structure has the advantage that a 50 movable bathing floor 9, may be supported at various heights therein for children's bathing or special sports. In Fig. 2, this platform is indicated as supported at the four corners of the well by suspension chains or cables 10, regulated

by winches 11. This enables the floor to be tilted from a shallow toward a deeper end and to be adjusted as desired with change of tide, etc. The trestle about the movable floor may be suitably screened as indicated at the right in Fig. 2 at 12, to confine the space above the floor while permitting the water to wash through freely.

A stairway or ladder 13, and other adjuncts may be provided for this protected elevated bathing pool.

If desired, a walk or gangway 14, may be extended from a pier or shore station to the platform of the sunken pool.

One or more diving boards, such as indicated 15 at 15, may be mounted on the platform directed either outwardly into open water or inwardly into the pool or both ways.

The barge may for cheapness and stability be made substantially rectangular and also relatively shallow, so as to cover sufficient area for a firm 20 foundation.

The means for sinking and raising may vary, but normally will consist of a suitable seacock 25 16, a venting connection or connections 17, and unwatering connections 18.

In the illustration, the barge is divided by partitions 19, 20, 21, 22, into a central and four surrounding compartments 23, 24, 25, 26, 27, and the flooding and unwatering connections are made to these compartments and valved so that they 30 may be operated as trimming tanks in the sinking and raising of the structure.

In the illustration, the seacock and the pumping 35 out line 18, are both connected with the same pipe system and this system comprises a main 28, Fig. 3, with branches 29, 30, 31, 32, 33, to the central and surrounding tanks controlled each by a valve 34. The seacock is connected in on this main by the line 35, and similarly, the pumping out line 18 is connected with the main by a lateral 36.

The seacock is shown as having a control stem 37, brought up above water level and the several tank valves are also shown as having operating handles 38, brought up to a level convenient for operating in the sunken condition of the barge.

In the sunken pool form of the invention first shown, these various controls are brought out to the edges of the barge, beneath the platform about the pool, being suitably connected with the valve stems as by the chain and sprocket extensions indicated at 39.

If desired, the pump for de-watering the barge may be carried by the barge as by mounting it on the diving platform 7, as shown at 40, in Figs. 1 and 2. This may be an advantage where it is 55

desired to shift the barge from time-to-time. In cases however, where the barge may remain sunk in a set position all season, the de-watering pipe 18, may simply be brought up to convenient position for coupling on a hose 41, Fig. 4, which may be connected with a pump on a boat or on a nearby pier, for example.

In the sunken condition, the barge serves as a firm foundation for diving, swimming and other sport purposes and a firm foundation of this sort is desirable as a look-out station for a life guard or the like.

In Fig. 4, a life guard platform is indicated at 42, and in the sunken pool form of the invention illustrated in Figs. 1 and 2, the cover 43, over the pump may be utilized as a seat or station for a life guard or other attendant.

The operation and use of the invention should be apparent from the foregoing. The apparatus in the floating condition is readily shifted from place to place. When a location is selected, the barge, while suitably guided by lines in various directions, may be sunk as rapidly or as slowly as desired, by controlling the seacock and the settling of the barge may be governed by operating the valves 34, controlling admission to the several compartments. This action also may be governed, if desired, by controlling release of air from the vent pipes 17, connected with the several tanks. After sinking, the seacock may be closed, or if desired, may be left open. When however, the barge is to be raised, the seacock should be closed and, with the valves to the several tanks opened according to the desired control, the barge may be de-watered through the pump line 18, raised and floated to another location and when it is to be put out of service, run up on shore or otherwise suitably stored.

In sinking or raising the barge, boats or pontoons may be arranged alongside and connected by lines with the barge to properly control and assure even settling and raising. By exercising such control, any dangers of tipping the barge may be avoided, while water is being let in to sink it, or on the other hand, is being pumped out to raise it. To break suction, a line may be dragged beneath the barge or other means employed, at the start of raising operations.

What is claimed is:

1. Diving apparatus for bathing beaches comprising a barge provided with means for sinking the same on bottom and with means for enabling the refloating of same, an open trestlework on said barge through which the water may wash when the barge is on bottom and an elevated diving platform mounted on said open trestlework.

2. Diving apparatus for bathing beaches comprising a barge provided with means for sinking the same on bottom and with means for enabling the refloating of same, an open trestlework on said barge through which the water may wash when the barge is on bottom, an elevated diving platform mounted on said open trestlework, said sinking and refloating means including a seacock, air venting means and dewatering connections for said barge, said air venting means and dewatering connections extending to above water level in the sunken condition of the barge and control means for the seacock extended up-

ward to within reach in sunken condition of the barge.

3. Diving apparatus for bathing beaches comprising a barge provided with a seacock and air venting means enabling the barge to be sunk on bottom, said vent means extending to above water level in the sunken position of the barge resting on bottom, means for closing the seacock operable when the barge is in sunken position, an open trestle on the barge, a diving board supported by said trestle above water level in the sunken position of the barge and dewatering connections extending from the barge to water level.

4. Diving apparatus for bathing beaches comprising a barge provided with a seacock and air venting means enabling the barge to be sunk on bottom, said vent means extending to above water level in the sunken position of the barge resting on bottom, means for closing the seacock operable when the barge is in sunken position, an open trestle on the barge, a diving board supported by said trestle above water level in the sunken position of the barge, dewatering connections extending from the barge to water level, said barge having trimming tanks and said various connections communicating therewith to enable controlled sinking and raising of the barge.

5. In diving and swimming apparatus, a barge having means for sinking the same into supported position on bottom and for refloating same, a raised platform on said barge, said platform having an open center defining a swimming pool and a floor to said pool over the top of the sunken barge.

6. In diving and swimming apparatus, a barge having means for sinking the same into supported position on bottom and for refloating same, a raised platform on said barge, said platform having an open center defining a swimming pool, a floor to said pool over the top of the sunken barge and means for variably positioning said floor of the pool.

7. In diving and swimming apparatus, a barge having means for sinking the same into supported position on bottom and for refloating same, a raised platform on said barge, said platform having an open center defining a swimming pool, a floor to said pool over the top of the sunken barge and operating devices for said sinking and refloating means positioned at the sides of the barge beneath the platform surrounding the pool.

8. Apparatus for diving and swimming uses, comprising a barge divided into water tight compartments, a single system of piping connected with the several compartments for admitting water thereto or for pumping water out of said compartments, a seacock connected with said piping, a pumping outline connected with said piping, vents from said compartments, valves in the piping for controlling flow to or from the several compartments and whereby said compartments may be used as trimming tanks in sinking the barge on bottom or in refloating the same and a diving and swimming platform mounted in elevated position upon the barge and adapted to be supported by the barge above water level when the barge is resting on bottom as a sunken foundation.

LOUIS GILIASSO.
